UNITED STATES PATENT OFFICE

142,702

DESIGN FOR A HOSPITAL GARMENT

Fannie Cohen, Tulsa, Okla.

Application March 22, 1945, Serial No. 118,624

Term of patent 14 years

(Cl. D3—26)

To all whom it may concern:

Be it known that I, Fannie Cohen, a citizen of the United States, residing at Tulsa, in the county of Tulsa and State of Oklahoma, have invented a new, original, and ornamental Design for a Hospital Garment, of which the following is a specification, reference being had to the accompanying drawing, forming part thereof.

I claim:

The ornamental design for a hospital garment, as shown.

FANNIE COHEN.
